SWIVEL HEAD FOR SKI POLE RINGS

Siegmund Werner, New York, N. Y.

Application March 21, 1947, Serial No. 736,199

9 Claims. (Cl. 280—11.37)

1

The invention relates to ski poles and relates more particularly to ski poles of the type carrying a ski pole ring to support the ski pole on the snow surface.

Desirable features of a ski pole include lightness, accurate positioning of the ring on the pole and a normally perpendicular relation of the ring on the pole, and these features, generally speaking, are usually obtained on ski poles now in use.

However, present ski poles are deficient in providing for a sufficient flexing of the ring on the ski pole to facilitate removing of the ring from an obstructing object. Furthermore, present ski poles usually do not admit of easy rotating of the ring on the pole.

It is, therefore, one of the principal objects of the invention to provide for a swivel connection between the ski pole and the ring.

Another object of the invention is the provision of a ring that is tilttable on the ski pole.

Another object of the invention is the provision of a ski pole ring that is freely rotatable on the pole.

A further object of the invention is to provide a ski pole ring that may easily be fastened to the ski pole and, if desired, removed therefrom.

A still further object of the invention is to provide a ski pole, carrying a ring, that is of simple construction and easy to manufacture.

Further objects and advantages of the invention will be set forth in part in the following specification and in part will be obvious thereto without being specifically referred to, the same being realized and attained as pointed out in the claims hereof.

With the above and other objects of the invention in view, the invention consists in the novel construction, arrangement and combination of various devices, elements and parts, as set forth in the claims hereof, one embodiment of the same being illustrated in the accompanying drawings and described in the specification.

For a fuller understanding of the nature and objects of the invention reference should be had to the following detailed description, taken in connection with the accompanying drawings, in which:

Fig. 1 is a perspective view of a ski pole carrying a ski pole ring;

Fig. 2 is an elevational view, partly in section, along line 2—2 of Fig. 1, on an enlarged scale, compared to Fig. 1, some parts being broken away;

Fig. 3 is a sectional view taken along line 3—3 of Fig. 2, some parts being broken away;

Fig. 4 is a fragmentary elevational view, partly in section, showing a ski pole tilted with relation to a ring; and

Fig. 5 is an extended view in perspective of the swivel head of the ski pole.

In carrying the invention into effect in one of the embodiments which has been selected for illustration in the accompanying drawings and for description in this specification, and referring now particularly to Fig. 1, a ski pole 11 is shown, carrying near the lower end a ski pole ring 12. Said ring 12 is detachably secured axially of said ski pole 11 by means of a swivel head 13 held about centrally in said ring 12 and permitting a tilting of the latter with relation to said ski pole 11.

Said ski pole 11 is tapered throughout its length, but the tapering is so slight that within any given part of the ski pole the same may be considered cylindrical for all practical purposes.

Said ski pole ring 12, as best shown in Figs. 2 and 3, comprises a ring 14 and a plurality of straps 16 radially arranged thereon. Each strap is secured at one end to said ring 14 by means of a rivet 17 or by other suitable fastening means, and extends with its other end towards the central portion of said ring 14. In said central portion there is provided the swivel head 13 that is secured to the other end of each strap 16 and thus supported within said ring 12.

Said swivel head 13 comprises an outer shell 18 and an inner shell 19, and the latter may freely revolve within the former. Said outer shell 18 surrounds a truncated spherical chamber 21 between two circular apertures 22 of said outer shell 18. Said apertures 22 are parallel to each other and oppositely disposed with relation to each other.

Said inner shell 19 is composed of two parts 23 forming together a split hollow sphere. Said parts 23 are opposite each other and each forming substantially a hollow hemisphere. Said inner shell 19 is split about a diameter of said spherical shell 18, and said two parts 23 face each other at a circular edge 24 formed by each part along said diameter. Each of said parts 23 has its circular edge 24 adjacent the other and each part projects from its circular edge axially and has an opening 26 opposite said circular edge and of smaller diameter than the same. A substantially cylindrical flange 27 surrounds each of said openings 26 and projects within each hemisphere for a portion towards the base 24 thereof.

Said split inner shell 19 has an outer diameter

that is slightly smaller than the diameter of said spherical chamber 21 of said outer shell 18. Thereby said inner shell is enabled to revolve within said chamber, said two half shells being maintained adjacently due to their enclosure within said chamber 21. The diameter of each opening 26 is smaller than the diameter of said aperture 22 and that, in turn, is smaller than the diameter of said split inner shell 19.

A portion of said ski pole 11 protrudes through said aligned openings 26 of said inner shell 19 and is frictionally engaged by said aligned flanges 27. Since that portion of the ski pole is substantially cylindrical, it fits well into said cylindrical flanges 27, and the taper of said ski pole together with the particular diameter of said openings 26 determines the location of said ski pole ring 12 on said ski pole 11, when secured thereon.

Said ski pole 11 protrudes at opposite sides from said inner shell 19 through said apertures 22, and said pole may be moved with relation to said outer shell 18 within the surface of a cone; this is best shown in Fig. 4, where the two extreme angular tilting positions of the ski pole with relation to the outer shell 18 is shown. Thereby, the tilting relation of the ski pole with relation to the ski pole ring 12 is substantially defined. However, an additional tilting of the ring with relation to the pole may be brought about through flexing of the straps 16, since the latter are made of leather or similar flexible resilient material.

Said outer shell 18 is composed of two symmetrically arranged sections 28, each carrying an integral annular flange 29 arranged about equatorially of said outer shell 18. Said two flanges are in abutment in a plane substantially midway between said two apertures 22. Said outer shell 18 is thus made of two sections, primarily for the purpose of facilitating the assembly of said swivel clamp 13.

Said flanges 29 are provided with a plurality of holes 31 and are held together by means of rivets 32 located in said holes 31. Said rivets 32 at the same time also pierce said centrally projecting ends of said straps 16 and thus secure said swivel clamp 13 within the center of said ring 12. However, the outer rims of said flanges may also be welded or brazed together, thereby uniting said flanges into a single flange of a single one-piece outer shell.

For mounting, two half-shells 23 are enclosed within two abutting sections 28, the holes 31 thereof aligned and the rivets 32 inserted therein and in pre-punched holes of the inner ends of said straps 16. Thereafter, the rivets are secured, and the ring 14 riveted onto the outer radially spaced ends of said straps 16, by means of rivets 17. Then, the split inner shell 19 is revolved in said chamber 21 until an opening 26 is visible within each aperture 22 and subsequently the ski pole 11 is inserted into the openings 26, thereby aligning them and frictionally engaging the inner walls of said flanges 27.

Due to the slight tapering of said ski pole 11, the inner ends of said flanges 27 will be slightly deformed according to the adjacent diameter of the ski pole part therein and thus, a strong frictional engagement intermediate said swivel clamp 13 and the ski pole part therein is assured.

Certain of the advantages of the invention have already been herein referred to. It may be useful, however, to allude particularly at this point to the great facility with which the swivel

clamp 13 and the entire ring 12 may be assembled, and the ease and simplicity lent toward frictionally securing the swivel clamp 13 to the ski pole 11.

I do not limit myself to the particular details of construction set forth in the foregoing specification and illustrated in the accompanying drawings, as the same refer to and set forth only one embodiment of the invention and it is obvious that the same may be modified, within the scope of the appended claims, without departing from the spirit and scope of the invention.

It is accordingly desired that in construing the breadth of the appended claims, they shall not be limited to the specific exemplification of the invention described herein.

Having thus described the invention, what I claim as new and desire to be secured by Letters Patent, is as follows:

1. A swivel arrangement designed to secure a ski pole ring to a pole comprising in combination: a truncated hollow member surrounding a spherical chamber, said member carried centrally in a ski pole ring and composed of two substantially identical parts oppositely arranged, each having a circular aperture of a diameter smaller than the diameter of said spherical chamber, and each carrying an annular flange opposite said aperture and arranged equatorially on said truncated member for abutment with and attachment to the opposite part, said flanges having a plurality of circularly disposed aligned holes for receiving rivets to interengage said parts and to secure said member centrally in a ski pole ring; and two hollow elements disposed within said spherical chamber and oppositely arranged with each other to form a sphere, said sphere having a smaller radius than that of said spherical chamber, thereby enabling said sphere to revolve within said spherical chamber freely, each of said elements forming substantially a hemi-sphere surmounting a circular edge, said elements facing each other at said circular edges and each element having a comparably small circular opening opposite said edge and a cylindrical flange around said opening extending towards the spherical interior of said element adapted to receive and to engage a round ski pole with said opening on the interior of said cylindrical flange; whereby said ski pole ring, when mounted on said pole, may be tilted with relation to said ski pole when said sphere is revolved on the interior of said truncated spherical member, the range of tilting depending on the diameter of said circular aperture and the width of said pole.

2. In a swivel arrangement for a ski pole ring, an outer hollow spherical member and an inner spherical member, the latter having a smaller diameter than the former for turning freely therein, said outer spherical member having two oppositely disposed circular apertures to form a truncated sphere therebetween and having an equatorially disposed annular flange for attaching said outer member centrally in a ski pole ring, said inner sphere having two oppositely disposed circular openings, each of said openings having a smaller diameter than said aperture, a cylindrical flange connected to each of said openings and extending for a portion towards the interior of said sphere, said sphere having a cut intermediate said two openings and parallel therewith, thereby splitting said spheres into two substantially similar opposite parts, said cylindrical flanges arranged to be brought in alignment for receiving and firmly gripping a portion

of a ski pole therebetween; said ski pole adapted to be angularly tiltable with relation to said ring owing to the difference in diameters between said openings carrying said pole and said aperture of said outer member.

3. The combination with a ski pole ring designed to be tiltably secured to a ski pole and freely to rotate thereon, said ski pole ring comprising a ring and strap means connected to said ring, of a swivel head secured to said strap means about centrally of said ring and comprising two elements forming substantially hemi-spheres oppositely arranged each having a circular edge adjacent one another and projecting therefrom axially and each having an opening surrounding an axis substantially perpendicular to said circular edge and having a smaller diameter than the same, said openings adapted to be aligned and to receive a ski pole extending through said hemi-spheres, said hemi-spheres disposed on the interior of a chamber of substantially truncated spherical shape, a housing having spherical walls forming on their interior said truncated spherical chamber surrounding at least partially said hemi-spheres and spaced therefrom sufficiently to permit free rotation of said hemi-spheres within said chamber, said housing including an annular flange having a plurality of holes, said housing having two opposite aligned apertures each substantially parallel with said flange, each aperture having a diameter smaller than the diameter of each hemi-sphere and larger than the diameter of said opening thereof carrying said ski pole, whereby said ski pole may be tilted with relation to said housing while moving said hemi-spheres during such tilting movement within the orbit of said apertures, and fastening means intermediate said strap means and said holes for securing said flange within said ski pole ring.

4. The combination with a ski pole ring designed to be tiltably secured to a ski pole and freely to rotate thereon, said ski pole ring comprising a ring and strap means connected to said ring, of a swivel head secured to said strap means about centrally of said ring and comprising two elements forming substantially hemi-spheres oppositely arranged each having a circular edge adjacent one another and projecting therefrom axially and each having an opening surrounding an axis substantially perpendicular to said circular edge and having a smaller diameter than the same, said openings adapted to be aligned and to receive a ski pole extending through said hemi-spheres, said hemi-spheres disposed on the interior of a chamber of substantially truncated spherical shape, a housing having spherical walls forming on their interior said truncated spherical chamber surrounding at least partially said hemi-spheres and spaced therefrom sufficiently to permit free rotation of said hemi-spheres within said chamber, said housing including an annular flange having a plurality of holes, said housing having two opposite aligned apertures each substantially parallel with said flange, each aperture having a diameter smaller than the diameter of each hemi-sphere and larger than the diameter of said opening thereof carrying said ski pole, whereby said ski pole may be tilted with relation to said housing while moving said hemi-spheres during such tilting movement within the orbit of said apertures, and fastening means intermediate said strap means

and said holes for securing said flange within said ski pole ring.

5. The combination with a ski pole ring designed to be tiltably secured to a ski pole and freely to rotate thereon, said ski pole ring comprising a ring and strap means connected to said ring, of a swivel head secured to said strap means about centrally of said ring and comprising two hollow elements forming substantially hemi-spheres oppositely arranged each having a circular edge adjacent one another and projecting therefrom axially and each having an opening surrounding an axis substantially perpendicular to said circular edge and having a smaller diameter than the same, each of said hemi-spheres having a flange surrounding said opening and extending to the interior of said hemi-spheres, said openings adapted to be aligned and to receive a ski pole extending through said hemi-spheres, said flanges adapted frictionally to engage the exterior of said ski poles for rigid connection thereto, said hemi-spheres disposed on the interior of a chamber of substantially truncated spherical shape, a housing having spherical walls forming on their interior said truncated spherical chamber surrounding at least partially said hemi-spheres and spaced therefrom sufficiently to permit free rotation of said hemi-spheres within said chamber, said housing including an annular flange having a plurality of holes, said housing having two opposite aligned apertures each substantially parallel with said flange, each aperture having a diameter smaller than the diameter of each hemi-sphere and larger than the diameter of said opening thereof carrying said ski pole, whereby said ski pole may be tilted with relation to said housing while moving said hemi-spheres during such tilting movement within the orbit of said apertures, and fastening means intermediate said strap means and said holes for securing said flange within said ski pole ring.

6. The combination with a ski pole ring designed to be tiltably secured to a ski pole and freely to rotate thereon, said ski pole ring comprising a ring and strap means connected to said ring, of a swivel head secured to said strap means about centrally of said ring and comprising two concentric spherical hollow shells, the inner shell sufficiently spaced from the interior of said outer shell to permit relative revolving of said shells, said outer shell comprising an annular flange about a spherical diameter thereof, said flange connected to said strap means, said outer shell having two opposite aligned apertures substantially parallel with said flange, each aperture having a diameter smaller than the diameter of said inner shell to expose a portion thereof, said inner shell split about midway to provide two separate half-shells, each half-shell having an opening of a diameter smaller than that of said aperture, said openings adapted to be aligned for receiving a portion of a ski pole therebetween to extend through said swivel head and to protrude therefrom, for securing said ski pole ring on said pole.

7. The combination with a ski pole ring designed to be tiltably secured to a ski pole and freely to rotate thereon, said ski pole ring comprising a ring and strap means connected to said ring, of a swivel head secured to said strap means about centrally of said ring and comprising two oppositely disposed substantially hemi-spherical parts and a housing surrounding a spherical chamber, said parts arranged to revolve in said chamber and substantially to remain oppositely

disposed therein to form a split spherical member and adapted to receive a portion of a ski pole in two aligned opposite openings thereof in frictional engagement, said housing having two apertures through which said pole protrudes for entirely projecting through said swivel head.

8. The combination with a ski pole ring designed to be tiltably secured to a ski pole and freely to rotate thereon, said ski pole ring comprising a ring and strap means connected to said ring, of a swivel head secured to said strap means about centrally of said ring and comprising two members, an outer member surrounding a spherical chamber and an inner member disposed in said chamber and arranged to revolve therein about an axis movable within the outline of a cone, whereby said members may be rotated and tilted with relation to each other, said inner member comprising two parts forming a split sphere and having two aligned openings to receive and to engage a substantially cylindrical ski pole, said outer member having two opposite circular apertures to permit insertion of said ski pole through said inner member, the diameter of said apertures being greater than the diameter of said pole sufficiently to permit tilting thereof with relation to said housing, when said pole is engaged by said inner member.

9. In a swivel head, for ski pole rings to be used in connection with a ski pole, an outer hollow shell of truncated spherical shape centrally

located within said ring, the combination therewith of a pair of oppositely disposed parts forming together an inner shell disposed within said outer shell, each part consisting of a hollow element forming substantially a truncated hemisphere extending between a circular edge formed along a spherical diameter of said hemisphere and a circular opening disposed parallel to said circular edge, spaced therefrom and having a smaller diameter than the same and a cylindrical flange extending within said hemisphere from said opening for a portion towards said circular edge, said circular edges of said parts normally adjacent each other and adapted to abut against one another, whereby said cylindrical flanges will be aligned to receive a portion of a ski pole in frictional engagement, each cylindrical flange having a wall being resiliently deformable sufficiently to permit deformation thereof by the insertion of said ski pole portion to insure a strong frictional interengagement therebetween.

SIEGMUND WERNER.
